His Attorney.

UNITED STATES PATENT OFFICE.

JOHN FLAMMANG, OF ST. LOUIS, MISSOURI, ASSIGNOR TO INLAND MACHINE WORKS,
OF ST. LOUIS, MISSOURI, A CORPORATION OF MISSOURI.

PROCESS FOR MAKING PISTON-RINGS.

1,295,147.

Specification of Letters Patent. Patented Feb. 25, 1919.

Application filed June 6, 1917. Serial No. 173,101.

To all whom it may concern:

Be it known that I, JOHN FLAMMANG, a citizen of the United States, residing at the city of St. Louis and State of Missouri, have 5 invented a new and useful Process for Making Piston-Rings, of which the following is a specification.

This invention relates to the art of manufacturing piston rings, and it consists in the 10 novel method of procedure in manufacturing piston rings in order to characterize them so that when applied to use within a cylinder the overlapping portions of the rings will form a perfect seal, and the pressure of the rings against the cylinder will 15 be properly distributed and apportioned throughout their circumference.

An object of the invention is to provide a 20 novel process for use in the art of manufacturing piston rings, whereby rings are produced by subjecting split rings having overlapping end portions to torsional action whereby they will be pressed together by the initial resiliency of the metal, and finishing 25 the ring after inversion of the overlapping ends thereof.

Another object of the invention is to provide a process for use in the art of manufacturing piston rings consisting in subjecting 30 split rings having overlapping end portions to torsional action whereby they are pressed together by the initial resiliency of the metal, and then changing the shape of the ring to give the greater portion thereof a 35 concentric shape and leaving portions of the overlapping ends thereon of smaller radii of curvature than the remaining portions of the ring, so that when the ring is compressed within a cylinder of the size for which it is 40 intended it will impart against the cylinder wall a uniform pressure all around without variation in the pressure, as in the case of rings of usual construction.

Other objects will appear from the following description, without specific mention thereof.

In the accompanying drawings, illustrating a ring in the different stages of its manufacture,

50 Figure 1 is an elevation looking toward the periphery of an annular casting from which the ring is manufactured.

Fig. 2 is an elevation looking toward the periphery of the casting after it has been 55 cut or split for a considerable portion of its

circumference to provide overlapping end portions.

Fig. 3 is an elevation looking toward the periphery of the ring before being expanded, showing the overlapping end portions of 60 Fig. 2 inverted on opposite sides of each other from their original positions.

Fig. 4 is an elevation looking toward the periphery of an annular casting split or cut to provide overlapping end portions of uniform width throughout their length, thus differing from the construction shown in Fig. 2 in which the overlapping end portions are tapered.

Fig. 5 is a side elevation of the ring before being expanded and having the end portions thereof set upon shorter radii of curvature than the remaining portions of the expanded ring.

Fig. 6 is a view illustrating the ring upon 75 an expanding arbor by which the shape of the ring is changed so that the end portions thereof are on shorter radii of curvature than the remaining portions of the ring.

Fig. 7 is a view of the ring detached from 80 the expanding arbor, more clearly illustrating the shape of the finished ring.

Fig. 8 is a view illustrating the ring compressed within a cylinder of the size for 85 which it is intended.

In Fig. 1 there is illustrated an annular casting consisting of two integrally united offset portions. At the point of union there is formed at one side a beveled shoulder 1 and on the opposite edge a beveled shoulder 2 which, in the finished form of the ring at least and preferably in its initial stage, matches the shoulder 1 so that when the ring blank is split and the overlapping ends thereof are inverted the shoulder 1 will extend within or under the shoulder 2 and thus limit outward expansion of the end portion containing the shoulder 1.

The ring blank also includes at another portion of its circumference a beveled shoulder 3 and on the opposite edge a beveled shoulder 4 which, in the finished form of the ring at least and preferably in its initial stage, matches the shoulder 3.

The annular ring blank provided with 105 these shoulders may be produced in any desired manner, preferably by casting. The next step in the formation of the ring consists in cutting or splitting the ring blank from the shoulder 1 to the shoulder 4, as 110

clearly illustrated in Fig. 2, in which the slot 5 extends spirally from the shoulder 1 to the shoulder 4, thus forming two overlapping tapered end portions separated by the 5 width of the slot 5. However, it is not essential that the overlapping end portions be tapered and they may be made of uniform width throughout their length if desired. In Fig. 4 I have illustrated a ring blank precisely similar to the ring blank shown in 10 Fig. 2, with the exception that the overlapping end portions thereof are of uniform thickness throughout their length. Since this is the only particular in which the ring 15 blank illustrated in Fig. 4 differs from the one illustrated in Fig. 2, the same reference characters are applied to both views of the drawing.

The next step in the manufacture of the 20 ring consists in twisting or inverting the ring blank to place the overlapping ends thereof on opposite sides from their initial positions so that they will be pressed together by the resiliency of the metal. The 25 ring blank thus twisted or inverted is illustrated in Fig. 3, which also illustrates the ring blank after it has been dressed or faced off preparatory to being expanded for the purpose of giving it the shape of the finished ring. Fig. 5 illustrates the ring blank 30 of Fig. 3 in side elevation, showing the shoulders 1 and 4 extending under or within the shoulders 2 and 3.

The ring blank is then placed upon an expanding arbor, as illustrated in Fig. 6, by which uniform radial pressures are applied to portions of the ring, but which leaves the 35 extremities of the overlapping portions of the ring curving on shorter radii of curvature than the remaining portions of the ring. While the extremities of the overlapping portions of the ring are somewhat modified they remain nevertheless upon approximately the same radii of curvature as they 40 were originally, which is approximately the proper radii of curvature for a piston and cylinder of the size for which the ring is constructed. While upon the expanding arbor the ring is subjected to heat or otherwise treated to set the metal in its changed 45 shape so that when the ring is removed from the arbor it will retain the shape given it thereby, in which the extremities of the overlapping portions of the ring are upon shorter radii of curvature than the remaining 50 portions of the ring, the said shorter radii of curvature being approximately the radii of curvature of the cylinder for which the ring is intended.

55 Fig. 7 illustrates the finished ring removed from the arbor and retaining its modified form and shape, it being understood that the overlapping ends retain the shape illustrated in Fig. 7, whether they are of the slightly 60 tapered construction illustrated in Figs. 2

and 3, or of uniform width throughout their length as illustrated in Fig. 4. The ring illustrated in Fig. 7 is the finished ring and is ready to be applied to a piston and placed within the cylinder. When the ring is 70 placed within the cylinder it is compressed to approximately the dimensions illustrated in Fig. 5, as will be clearly understood by reference to Fig. 8, in which the finished ring is illustrated upon the piston and with 75 in the cylinder.

From the foregoing it will be understood that I have provided a simple and inexpensive procedure for constructing a ring, so that the overlapping portions thereof will 80 be pressed together by the inherent resiliency of the metal without changing the molecular construction by heat or other treatment. The variation in the radii of curvature of the overlapping portions of the 85 ring may be effected otherwise than by the specific treatment described, as, for instance, by peening, or by hammering, though I have found in practice that the mode described is highly satisfactory.

90 It is apparent that the order of the different operations may be varied and that the ring may be set in its expanded shape to vary the radii of curvature before the ring blank has been twisted or faced off to the 95 form illustrated in Fig. 3. Obviously, the twisting or inversion of the ring to place the overlapping ends thereof on opposite sides from their initial positions, so that they will be pressed together by the inherent 100 resiliency of the metal, may be effected after removal from the expanding arbor instead of before being placed upon the arbor. There are other variations which will be readily apparent to those skilled in the art 105 to which this invention relates, and which do not require specific mention but which are clearly within the scope of my present claims. Therefore, I do not confine myself to any specific order in which the operations 110 are performed, but what I claim and desire to secure by Letters Patent is:—

1. The process of forming a piston ring with overlapping end portions pressed together by the initial resiliency of the metal, 115 which comprises splitting a ring on a cut extending circumferentially to provide the overlapping end portions, inverting the overlapping end portions to place them on opposite sides of each other from their original positions, and finishing the ring while the overlapping end portions are on opposite sides of each other from their original positions and are pressed together by the 120 initial resiliency of the metal.

125 2. The process of forming a piston ring having overlapping end portions, which comprises splitting a solid ring in a cut extending circumferentially to provide overlapping end portions, inverting the split 130

ring thereby formed to place the overlapping end portions on opposite sides of each other from their original positions, and facing off the ring while the overlapping ends thereof are inverted and are pressed together by the initial resiliency of the metal to form parallel side walls on the ring.

3. The process of forming a piston ring having overlapping end portions, which 10 comprises splitting a solid ring in a long cut extending circumferentially, inverting the split ring to place the overlapping end portions thereof on opposite sides of each other from their original positions, facing 15 off the ring in its inverted position to form parallel side walls, and expanding the ring to a size in excess of the cylinder for which it is intended.

4. The process of forming a piston ring 20 expanded to a size in excess of the cylinder for which it is intended and having overlapping end portions, which comprises inverting the overlapping end portions to place them on opposite sides of each other from 25 their original positions, whereby they will be pressed together throughout their length by the initial resiliency of the metal, and facing off the side edges of the ring while the overlapping ends thereof are inverted from 30 their original positions and pressed together by the initial resiliency of the metal to form parallel side walls of the ring.

5. The process of forming a piston ring having overlapping end portions, which 35 comprises splitting a solid ring in a long cut extending circumferentially, inverting the overlapping end portions formed thereby to place them upon opposite sides of each other from their original positions, and forming 40 parallel side walls for the ring in its inverted form.

6. The process of forming a piston ring having overlapping end portions, which comprises splitting a solid ring in a long 45 cut extending circumferentially to form the overlapping end portions, inverting the overlapping end portions to place them on opposite sides of each other from their original positions, expanding the ring by the application of radial pressure thereto, and thereafter treating the ring to set the material thereof to cause it to retain said expanded form.

7. The process of forming a piston ring, 55 which consists in splitting a solid ring circumferentially to form overlapping end portions, twisting the ring to place the overlapping end portions on opposite sides of each other from their original positions, 60 forming parallel side walls for the ring while the overlapping ends thereof are in-

verted as aforesaid, expanding the ring to a size in excess of the cylinder for which it is intended, while leaving the extremities of the overlapping portions on shorter radii 65 of curvature than the remaining portions of the ring, and treating the ring to set the material thereof in its expanded form.

8. The process of forming a piston ring, which consists in splitting a ring circumferentially for a portion of its circumference to provide overlapping end portions, inverting the overlapping end portions to place them on opposite sides of each other from their original positions, expanding the ring 75 by the application of uniform radial pressures thereto, leaving the end portions of the ring upon shorter radii of curvature than the remaining portions of the expanded ring, and exposing the ring to the action of 80 heat to set the material thereof in the shape aforesaid.

9. The process of forming a piston ring having overlapping end portions, which comprises splitting a solid ring in a long cut 85 extending circumferentially to form the overlapping end portions, inverting the overlapping end portions to place them on opposite sides of each other from their original positions, forming parallel side walls 90 upon the ring while the overlapping ends thereof are inverted as aforesaid, expanding the greater portion of the ring to a size in excess of the cylinder for which it is intended while the extremities of the overlapping portions remain upon shorter radii of curvature than the remaining portions of the ring, and treating the ring to set the metal thereof in the shape aforesaid.

10. The process of forming a piston ring having overlapping end portions, which comprises splitting a solid ring in a cut extending circumferentially to provide the overlapping end portions, inverting the split ring thereby formed to place the overlapping end portions on opposite sides of each other from their original positions, expanding the ring by the application of radial pressure thereto until the greater portion of the ring is upon radii of curvature in excess of the radii of curvature of the cylinder for which the ring is intended leaving the end portions of the ring upon shorter radii of curvature than the remaining portions, treating the ring to set the material thereof in the form aforesaid, and facing off the side edges of the ring while the end portions thereof are inverted from their original positions to form parallel side walls.

In witness whereof, I have signed this 120 specification.

JOHN FLAMMANG.
